CLAIM

The ornamental design for a notebook computer, as shown and described.

DESCRIPTION

FIG. 1 is a front, right, top perspective view of a notebook computer showing our new design;

FIG. 2 is a rear, left, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' of FIG. 1;

FIG. 10 is an enlarged view of the portion, labeled '10' of FIG. 7;

FIG. 11 is a front, right, top perspective view thereof in an alternate state of use;

FIG. 12 is a rear, left, top perspective view thereof;

FIG. 13 is an enlarged view of the portion, labeled '13' of FIG. 11; and,

FIG. 14 is an enlarged view of the portion, labeled '14' of FIG. 12.

Dot-dash broken lines seen in the drawings define the bounds of the claimed design and form no part thereof. Dot-dot-dash broken lines represent boundaries of the enlarged portions and form no part of the claimed design. All other broken lines illustrate portions of the notebook computer that form no part of the claimed design. The unshaded concentric circular surface shown between the solid line and dashed broken line forms no part of the claimed design.
